UNITED STATES PATENT OFFICE.

ALICE F. LEACH, OF BOSTON, MASSACHUSETTS.

PORTABLE TENT.

941,458.

Specification of Letters Patent. Patented Nov. 30, 1909.

Application filed July 14, 1908. Serial No. 443,431.

To all whom it may concern:

Be it known that I, ALICE F. LEACH, a citizen of the United States, residing at Boston, in the county of Suffolk and State of 5 Massachusetts, have invented certain new and useful Improvements in Portable Tents, of which the following is a specification, reference being had therein to the accompanying drawings, which form a part thereof.

10 My invention relates to tents and more particularly to a class of portable tents adapted to be carried by hand and capable of being quickly raised and taken down.

The main object of the invention is to provide 15 a portable tent, the pole of which will be made of a plurality of separable sections, and the top section of each pole will be provided with means adapted to not only distend the top of the cover so as to dispense 20 with a ridgepole, but will shape the said top and both reinforce it and afford a watertight lining therefor beneath said top.

A still further object of the invention is to provide a portable knockdown tent where- 25 in the top and sides may be made of light material and yet have the top waterproof by reason of separate water-resisting packing therefor.

A still further object is to provide a tent 30 of this character wherein the top and sides will be in one integral piece, and will be accurately positioned and held from a point centrally of the top of the distending frame. And a still further object is to provide a de- 35 vice of this character which will be compact in form, light in weight and comparatively inexpensive to manufacture.

The invention consists in the novel fea- 40 tures of construction and combination of parts herinafter set forth and described, and more particularly pointed out in the claims hereto appended.

Referring to the drawings,—Figure 1 is a front view of a tent embodying my invention, with the flap thrown over to one side and a portion of the top broken away to disclose the inner umbrella top. Fig. 2 is a detail view of the end of that section of the standard or pole carrying the clamp mem- 50 ber. Fig. 3 is a view of the tent folded for transportation; and Fig. 4 is a view of a section of the center of the top showing the reinforced opening by means of which the tent-cover is positioned relative to the um- 55 brella top.

Like letters refer to like parts throughout the several views.

In the present embodiment of my invention shown in the drawings, the center pole of the tent is shown as being composed of a 60 plurality of sections *a*, *b*, *c*, provided with suitable coöperating means whereby they may be united to form a perfectly rigid pole. The lower end of the section *a* is pointed, as at *a'*, to facilitate the mounting of the pole 65 in the ground or beach, and the upper end thereof is provided with a metallic socket *a''*, adapted to receive a tenon *b'* on the section *b*. The upper end of the section *b* is pro- 70 vided with a holder *d*, the detail construction of which will be referred to at greater length hereinafter. The section *c* consists of the handle of an ordinary umbrella.

The holder *d* comprises two jaws, *e*, *f*, the insides of which are shaped to conform to the 75 section *c*, one of which jaws *f* is hinged at *g* to the other jaw *e* and the socket *h* by means of which the holder is attached to the section *b*. One of said jaws, as *f*, has its forward edge recessed, as at *f'*, and the other jaw is 80 pivotally mounted therein in a line with said recess and screw *e'* carrying a thumb-nut *e''*, by means of which said jaws may be closed upon the section *c* and clamp it firmly be- 85 tween them. The section *c* carries an ordinary folding metallic umbrella frame *i*, having a suitable waterproof covering *j* so that the raising of the umbrella will not only form the top of the tent, but will serve as a backing for and a reinforcement to the tent 90 cover or canvas. The frame *i* will also, by its flexibility, aid in setting up and striking the tent by giving in a manner to permit the lower edges of said cover to be staked to the ground and thereafter tightening the 95 same so as to hold the tent cover in the extended position. The umbrella section *c* is provided with an ordinary ferruled end *c'*.

Tent cover *k* comprises a top section adapted to fit over and conform to the um- 100 brella *j* when the same is raised and an outwardly flared side section falling from this top section for a distance substantially equaling the length of the center pole, allowing for that spreading at the bottom 105 necessary to deflect water and afford more available space within the tent. The top section and sides may be made after any desired pattern, and in as many sections as may be desired according to the dimensions 110

of the tent or the economical cutting of the material, and the material employed is immaterial, although preferably heavy duck, or like canvas, is used.

- 5 Centrally of the top section of the tent cover *k* is an opening reinforced by suitable stitching or other reinforcing means *k'*, which opening is adapted to receive the ferruled end *c'* of the umbrella stick section. 10 *c* and accurately position the top section of the tent cover relative to the umbrella frame and cover and hold it in this position.

The lower edge of the side sections of the cover *k* is provided with a plurality of loops *k*² adapted to fit over pegs *m* which form a part of the portable tent equipment. The tent cover is provided with a flap *n* for closing the tent opening, suitable ties *n'* being provided for holding said flap in the closed 20 position.

When it is desired to transport the portable tent outfit, the center pole is taken down and the sections thereof separated, the umbrella closed and the cover *k* rolled upon 25 itself and upon the pegs *m*, and the entire outfit fastens together by any suitable means, as a shawl-strap *o*. When folded in this position the length over all will not exceed that of the ordinary umbrella, and the gross 30 weight will be approximately eight pounds.

When it is desired to use the tent, the pole *a* is assembled by placing the reduced end *b'* in the socket *a*² and securing the handle of the umbrella section *c* in the holder *d*. 35 this last is accomplished by the clamp-nut *e*² from the jaw *f* swinging the screw *e'* clear of the recessed portion *f'* and opening the jaw *f* wide so as to permit the insertion of said section between said jaws. Thereupon, this operation is reversed and the jaws *e*, *f*, clamped firmly upon the section *c* through the closing of said jaws by means 40 of the screw *e'* and the thumb-nut *e*². During the assembling of the pole, the umbrella frame *i* may be extended or not, as desired. The center pole is then placed in the ground 45 by means of the spiked end *a'* and forced thereinto to an extent to give rigidity to the pole.

50 The umbrella being raised, the cover *k* is thrown thereover and the reinforced opening *k'* is passed over the ferruled end *c'* of the umbrella section *c*, the sides *k* being permitted to drop over the edge of the umbrella 55 *j* and frame *i* to the ground. If desired, the ferruled end *c'* may be brought into convenient reach by releasing the holder *d* and lowering the section *c* for this purpose, the umbrella section *c* thereafter being brought 60 to the desired elevation and clamped in this position. It will be observed that this construction gives a double top to the tent so that no rain can enter the opening *k'* or be driven between the sides *k* and the top of the 65 tent. This construction also accurately po-

sitions both the top and the sides of the tent by a single operation and dispenses with all means of attachment at the top and the sides *k* and about the umbrella frame supporting same. The pegs *m* are then inserted about 70 the tent at the desired distances and the sides *k* stretched toward them and secured thereto by passing the loops *k*² thereover. This distends the bottom of the tent to the desired extent and this operation is facilitated by reason of the elasticity of the frame *i* which will give, at any time, sufficiently to adapt the tent-cover to any irregularities in the placing of the pegs. Incidentally, the opening *k'* engaging the ferruled end *c'* 80 will prevent the displacement of the top section of the tent-cover by this stretching operation.

When assembled, as above stated, the umbrella frame and cover will not only serve 85 to shape the top section of the tent body, but will reinforce it and serve as a water-proof backing to an extent to permit the use of much lighter material in the entire tent body, thus not only reducing the weight of 90 the entire structure, but the cost of the material of which the tent body is composed.

It is not my intention to claim broadly 95 the use of an umbrella in a portable tent, such being old and well-known in the art, but I believe it to be new to provide, in combination with an umbrella top, a tent cover comprising a top section adapted to fit over and conform to said umbrella top and substantially integral side sections 100 extending from this top section to a point adjacent to the ground and I intend to claim such. It is not my intention, however, to limit my invention to the precise details of construction shown in the drawings, it being 105 apparent that such may be carried without departing from the spirit and scope of the invention.

Having described the invention, what I 110 claim as new and desire to have protected by Letters-Patent, is:—

1. In a portable tent, the combination with a center pole comprising a plurality of sections and means whereby said sections may be separably connected, a collapsible 115 umbrella frame carried by the uppermost section, and a waterproof covering therefor, of a tent cover having a top portion adapted to fit over and conform to said frame and its covering, and side portions attached to, 120 and pendent from, said top portion.

2. In a portable tent, the combination with a center pole comprising a plurality of sections and means whereby said sections may be separably connected, a collapsible 125 umbrella frame carried by the uppermost section, the end of said section, or the umbrella tip, projecting beyond said frame, and a waterproof covering on said frame, of a tent cover having a top portion having 130

an opening therein adapted to receive said projecting end, or tip, and being adapted to fit over and conform to said frame and its covering, and side portions attached to, and pendent from, said top portion.

3. In a portable tent, the combination with a center pole comprising a plurality of sections, means whereby said sections may be separably connected, a plurality of jaws carried by the uppermost of said sections, clamping means whereby said jaws may be closed or released to be opened, and an umbrella section comprising a stick or handle adapted to be engaged by said jaws, a collapsible frame carried thereby, and a waterproof covering on said frame, said stick or handle having its end or tip projecting outwardly beyond said frame of a tent cover having a top portion adapted to fit over, and conform to, said frame and its covering, side portions attached to, and pendent from said top portion, loops attached to the bottom of said pendent sides, adapted to engage ground pegs, and a closure flap, said top portion having a central reinforced opening therethrough adapted to receive said projecting end or umbrella tip.

4. In a portable tent, the combination with a center pole comprising a plurality of sections, means whereby said sections may be separably connected, a plurality of jaws

carried by the uppermost of said sections, clamping means whereby said jaws may be closed or released to be opened, and an umbrella section comprising a stick or handle 30 adapted to be engaged by said jaws, a collapsible frame carried thereby, and a waterproof covering on said frame, said stick or handle having its end or tip projecting outwardly beyond said frame of a tent cover 35 having a top portion adapted to fit over, and conform to, said frame and its covering, side portions attached to, and pendent from said top portion, loops attached to the bottom of said pendent sides, adapted to engage ground pegs, and a closure flap, said top portion having a central reinforced opening therethrough adapted to receive 40 said projecting end or umbrella tip.

In witness whereof, I have hereunto affixed my signature this 26th day of June, 1908, in the presence of two witnesses.

ALICE F. LEACH.
